FREQUENCY INDICATING AND COUNTING ARRANGEMENT

Albert E. Bachmann, Cedar Rapids, Iowa, assignor to Collins Radio Company, Cedar Rapids, Iowa, a corporation of Iowa

Application September 30, 1947, Serial No. 777,045

17 Claims. (Cl. 116—124)

1

This invention relates to frequency selection systems and more especially to a frequency counter and indicator for use in such systems.

A principal object of the invention is to provide an improved mechanical counting device which has a plurality of indicator dials or drums one of which indicates successive relatively widely different numbers of turns of a control shaft or the like, and another dial or drum which indicates uniform increments between said successive widely different numbers of turns.

Another principal object is to provide a mechanical counting device having a series of indicator dials which are successively and cumulatively operated by one control to indicate successive and relatively coarse settings of a shaft or the like, and another dial to indicate uniform incremental settings between said coarse settings. The said series of coarse dials can be set independently and cumulatively by their respective control knobs. However the incremental dial can be independently set to indicate a series of subdivisions between the coarse settings of said series of dials. The arrangement is such that, if desired, continuous rotation of the incremental dial can also cause the cumulative setting of the said series of dials.

Another object is to provide a novel mechanical counting dial for an arrangement which is required to be adjusted to any one of a series of coarse settings, and which is also required to be adjusted to any integral subdivision between successive coarse settings.

Another object is to provide an improved frequency counting device for wave frequency generator or selector systems, wherein the system can be adjusted to any one of a series of frequencies relatively widely spaced in the frequency spectrum, and also to any desired incremental frequency.

A feature of the invention relates to a wave frequency generator or selector system having a coarse frequency selector channel, and an incremental or fine frequency selector channel, the settings of both channels determining a single desired output frequency, which settings are controlled by the number of turns of respective control shafts, in conjunction with a special counting dial having a plurality of dial sections arranged to be set respectively in accordance with said control shafts. The dial section for the incremental frequency is arranged to be adjusted independently of the other dial section, and said other dial section is constituted of a series of successively cumulative digit dials all of which

2

can be adjusted independently of the incremental dial. However the lowest digit dial of said other dial section can also be controlled cumulatively by a predetermined number of complete turns of said incremental dial.

Another feature relates to a numerical counting dial arrangement having two dial sections, one section consisting of a single rotatable dial, and the other section consisting of a series of cumulative rotatable dials. Control means are provided for separately operating the two dial sections, but one of the dials of said other section is arranged to be operated cumulatively by the first dial section.

Another feature relates to a direct reading frequency counting mechanism for wave frequency generators or selectors of the type which can be set in successive coarse steps to produce any one of a series of frequencies relatively widely spaced in the frequency spectrum, and can also be set in incremental steps to produce any desired incremental frequency within the range of each coarse setting.

Another feature relates to an improved direct reading frequency counting and indicating dial for use with wave frequency generating or selecting systems of the kind disclosed for example in application Serial No. 650,666, filed February 27, 1946, and issued as U. S. Letters Patent No. 2,445,664.

A still further feature relates to the novel organization, arrangement, and relative interconnection of parts which cooperate to provide an improved direct reading dial for a multi-frequency selection system.

Other features and advantages not particularly set forth will be apparent after a consideration of the following detailed descriptions and the appended claims.

40 In the drawing which represents one preferred embodiment,

Fig. 1 is a front view of the frequency counter and indicator device according to the invention.

Fig. 2 is a composite mechanically schematic and electrically schematic diagram of a frequency selecting and indicating system according to the invention.

Fig. 3 is an isometric view of the mechanism represented in mechanically schematic form in Fig. 2.

Fig. 4 is a detailed view of part of the mechanism shown in Fig. 3.

The invention finds its primary utility in systems for selecting any one of a very large number of wave frequencies which are relatively closely

spaced in the frequency spectrum, by first selecting a frequency range within which the desired frequency is situated, and then incrementally obtaining the desired frequency. A typical system of this kind is disclosed in said application Serial No. 650,666, and is represented schematically in Fig. 2 by the master frequency source 10 and by the associated coarse frequency channel selection circuit 11, the fine or incremental frequency channel selection circuit 12, and a suitable load circuit such as the radio transmitter 13 with its associated antenna 14. As described in said U. S. Letters Patent, the source 10 can be any well-known device for generating simultaneously a very large number of frequencies, for example it may take the form of an electron tube oscillator which is connected through a harmonic generator to produce the harmonic frequencies, or it may take the form of a multivibrator for producing these frequencies. In certain kinds of radio transmission it is necessary to switch the radio transmitter 13 rapidly to any one of a very large number of radio frequencies, and merely for explanation it will be assumed that these frequencies lie between one megacycle and ten megacycles with successive final frequency spacings of 250 cycles per second. As also described in said U. S. Letters Patent, the coarse frequency selecting channel 11 is arranged to be set in a step-by-step manner by means of a hand-wheel or knob 15, and the fine or incremental channel 12 is arranged to be set by the respective hand-wheel or knob 16. It will be assumed that the knob 15 is arranged to be turned during each revolution through four equal steps approximately 90° apart, and that each step corresponds to a twenty-five kilocycle range of the selector 11. Also for purposes of explanation, it will be assumed that the knob 16 is likewise arranged to be operated during each revolution through four successive steps each representing an incremental frequency of 250 cycles per second from the selector 12. The knobs 15 and 16 are also mechanically coupled through respective mechanisms to be described, to the frequency indicating and counting dial 17. This dial is constituted of three sections 17a, 17b and 17c. The section 17a consists of a single wheel or drum carrying four frequency markings equally distributed around the periphery, namely 000 and 250, 500 and 750. The dial section 17a is thus arranged to be operated through suitable gearing and shafting in unison with the knob 16. Thus for each of the four successive positions of knob 16, the dial section 17a will indicate one of the four above-mentioned incremental frequencies in cycles per second. The dial section 17b consists of a dial wheel 18 with ten equally spaced numerals and is arranged to be operated in a 1:10 ratio with respect to section 17a under control of knob 16.

On the other hand, the dial section 17c consists of three separate dial wheels 19, 20, 21. Each of these wheels 19 to 21 carries ten equally spaced digits 0 to 9 around its periphery in the manner well-known in dial counters. The dials 19 to 21 are arranged to be cumulatively operated in sequence. The dial 18 is also arranged to be set in a 10:1 ratio with respect to dial 19 under control of an intermittent gearing which is controllable by knob 15. Thus, when the dial 18 makes one complete turn either as a result of turning knob 15, or as a result of turning knob 16, it advances the dial 19 through one-tenth of a turn. Likewise, when the dial 19 makes one complete turn, it advances the dial 20 through

one-tenth of a turn, and a similar arrangement exists between the dials 20 and 21. Since cumulative mechanisms of this general type are well-known in the dial counting art, description thereof is not necessary herein. Thus dial 18 is arranged so that it can be set either by the knob 15 or by the knob 16. However, the knob 15 is so connected, that for each quarter-turn thereof between its respective positions *a*, *b*, *c* and *d*, it advances dials 18, 19, by twenty-five kilocycle steps. In other words, the output of the selector 11 is varied one hundred kilocycles for each complete revolution of knob 15. In the particular setting illustrated in Fig. 2, the selector 11 is producing an output frequency of 2313 kilocycles. If the knob 15 is turned so as to bring the indicator pointer "e" into the "c" position, the selector 11 will produce a frequency of 2338 kilocycles which will be indicated on the dial section 17b. Likewise, if the knob 15 is turned so that the indicator pointer "e" is in position "b," the selector 11 will produce 2363 kilocycles which will likewise be indicated on dial section 17b. On the other hand, the knob 16 for each complete rotation causes the output of the frequency selector channel 12 to vary over a range of 1000 cycles per second, or 250 cycles per second for each quarter-revolution of knob 16. Consequently, for twenty-five complete revolutions of knob 16, one hundred uniform incremental frequencies can be selected for each twenty-five kilocycle setting of selector 11.

The mechanical controls between the knobs 15 and 16 and the counting dial 17, are schematically indicated in Fig. 2. Thus the knob 16 is connected through suitable shafting 22, 23 and suitable gearing to operate the dial 17a in unison therewith, at the same time giving rise to increments in the output frequency of selector 12 of 250 cycles per second. The knob 16 is also coupled by shafting 22, 23 and an intermittent gear arrangement 24 having a ratio of five to one. That is, for each complete turn of knob 16, the shaft 25 is advanced one step. The shaft 25 is coupled to the ring gear 29a of a differential gear unit 29 through suitable step-down gear 27a having a step-down ratio of two to one. Shaft 28 which is attached to gear 29a drives the dial 18 through one to one ratio gears 53, 54. Thus, there is a ten to one step-down intermittent ratio between knob 16 and dial 18, so that for every complete turn of knob 16 the dial 18 is advanced one-tenth of a turn. The intermittently rotatable shaft 25 is also coupled to another shaft 31 through an intermittent spur gear combination 32a, 32b, with a step-down ratio of five to one. Shaft 31 is coupled to the ring gear 36a of another differential gear unit through step-down gears 34a, 34b with a step-down ratio of twelve to five. The sun gear 36b of this differential is then coupled to shaft 35 through gears 64, 65 having a one to one gear ratio. Shaft 35 is then coupled to shaft 37 through an intermittent spur gear arrangement 38a, 38b having a step-down ratio of ten to six. Shaft 37 drives the dial 19 which for every complete turn drives the dial 20 one-tenth of a turn. By following through the above-described shaft and gear arrangement, it will be seen that the step-down ratio between knob 16 and dial 19 is one hundred-to-one. Thus, by rotating knob 16, the dials 17a, 18 and 19, continuously indicate the frequency to which the transmitter 13 is being set. The mechanism for controlling the channel 11 and the dials 18, 19, 20 in their twenty-five kilocycle steps independently

of knob 16, comprises the knob 15, which is coupled through shafts 39, gears 55, 56, 57, 58, 59, to shaft 40, and thence through gears 60, 69, 70, the differential gear arrangement 28, but with a step-down ratio of two to one, and thence to the shaft 28, which drives dial 18. The knob 15 is also coupled through shaft 39, thence through gears 59, 62, 63 to shaft 41 with a step-down ratio of six to five. Shaft 41 is also coupled to shaft 35, through gears 64, 65 and the differential gear arrangement 36 but with a step-up ratio of one to two. Shaft 35 as above described is coupled to dial 19 through the step-down intermittent gears 38a, 38b having a ratio of ten to six. By following the above-described shafting and gearing connections, it will be seen that dials 18 and 19 continuously indicate the twenty-five kilocycle increments produced by quarter-rotations of knob 15. By means of the differential gear arrangements 29 and 36, it is possible to operate the dials 18, 19, 20, and 21 independently of the dial 17a. Likewise, it is possible to operate the dial 17a so as to obtain any other desired, uniform, incremental setting between the successive twenty-five kilocycle settings of dials 18 and 19. The movement of either of the knobs 15 or 16 does not affect the previous setting of the other knob.

The above-described arrangement is particularly useful where the transmitter 13 is required to be switched rapidly to widely different frequencies. For example, if the transmitter 13 is operating at a frequency of 2,313.250 kilocycles as indicated by the setting of the equipment in Fig. 2, and it is required to be shifted to 2,463.250 kilocycles, all that is necessary is to turn the knob 15 through five quarter-revolutions so that the indicator point "e" registers in the position "c." This will automatically add 125 kilocycles to the indicated setting of the dial 17, and will automatically adjust the transmitter 13 to the new frequency. If ordinary counter mechanisms were employed, employing a single knob such as the knob 16, it would be necessary to turn the dial 17 a very great number of times in order to arrive at the final setting. During this adjustment the transmitter would be inoperative, and valuable transmission time would be lost.

Referring to Fig. 3, there is shown in isometric perspective the mechanical connections between the two knobs 15, 16, and the respective dial wheels. The parts of Fig. 3 which correspond functionally to those of Fig. 2, bear the same designation numerals. The knob 16 is fastened to the shaft 43 which controls the setting of the fine selection circuit 12. Likewise, the knob 15 is fastened to the shaft 44 for controlling the coarse frequency selection circuit 11. Also fastened to the shaft portion 23 is a bevel gear 45 which meshes with a corresponding bevel gear 46 attached to shaft 22. Shaft 22 carries the disc 47 and the laterally extending driving pin 48 which cooperates with the slotted driven disc 49. Disc 49 is fastened to shaft 50 which carries the intermittent locking gear 51 which is in engagement with the corresponding notched disc 52 fastened to shaft 22. Thus after each five revolutions of shaft 22, the shaft 25 is advanced one revolution. The shaft 25 also drives the intermittent spur gear arrangement 32 comprising the spur gears 32a, 32b, and the corresponding intermittent locking gears 32c, 32d. Gear 32b is fastened to shaft 31 and the gearing is such that there is a step-down gear ratio of five to one between shafts 25 and 31. Shaft 22 also carries a spur gear 22a which meshes with an idler gear 22b, which in

turn meshes with the gear 22c attached to the dial section 17a, so that this dial section rotates in unison with the knob 16. Shaft 31 drives the spur gears 34a, 34b, having a step-down ratio of twelve to five. Gear 34b is in mesh with the ring gear 36a of the differential 36. Likewise the spur gear 27a on shaft 25 is in mesh with the ring gear 29a of the differential 29. The differential gear 29 consists of a planetary gear system comprising planetary gears 29b, 29c, (see Fig. 4), which are affixed to the common shaft 29d passing through the ring gear 29a. The planetary gears 29b, 29c, are in mesh with their respective sun gears 29e, 29f. Sun gear 29e drives a gear train 53, 54, which in turn drive the dial 18.

The control knob 15 rotates the bevel gears 55, 56, 57, 58, which in turn drive shaft 40 as well as gears 59, 60. Gear 59 drives a gear train 61, 62, 63, which in turn drive the sun gear 36b of the differential 36. The shaft of sun gear 36b carries a gear 64 which meshes with a corresponding gear 65 attached to the intermittent gear 38a. Gear 38a drives the corresponding spur gear 38b under control of the associated intermittent locking gears 38c, 38d. Gear 38d, through suitable spur gears 66, 67, drives the dial 19 by means of shaft 68 which passes through the dials 20, 21. Gear 60, through gears 69, 70, is coupled to the sun gear 29f (see Fig. 4) of the planetary or differential gear system 29. Thus, by means of the two planetary gear systems 29 and 36, it is possible to provide independent yet coordinated control of dials 18 and 19 by means of either of the knobs 15 or 16. It will be understood, of course, that the dial 17 can be continuously operated if the knob 16 is continuously rotated. In other words, one complete turn of knob 16 causes one complete turn of dial 17a and one-tenth of a complete turn of dial 18. When dial 18 has made one complete turn under control of knob 16, dial 19 rotates one-tenth of a turn intermittently under control of shaft 68 and suitable Geneva and step-down gear ratios. Dial 19 then drives dials 20 and 21 in a standard counting drum arrangement. However, as pointed out above, this manner of operation of the dial 17 would consume a great amount of time if the transmitter 13 is to be successively tuned to very widely different frequencies. For this reason, the knob 15 is used to control the setting of the sections 17b and 17c, and the fine or interpolation setting of the dials 17a and 17b can be controlled by knob 16. Thus there is provided a direct indication of the frequency of the transmitter 13, and the two controlling knobs 15 and 16 are mechanically isolated during the coarse setting of dial 17 and during the interpolation setting thereof.

While one particular embodiment has been described, it will be understood that various changes and modifications may be made therein without departing from the spirit and scope of the invention.

What is claimed is:

1. The combination of a device which is arranged to be adjusted to any desired setting by coarse steps and by fine steps and including rotatable control shafts respectively for the coarse and fine steps, and means to count and indicate directly the number of turns required for each shaft to cause said device to assume its desired setting, the last-mentioned means including a calibrated numerical dial section for the coarse setting, a second calibrated numerical dial section for the fine setting, means to set the coarse dial section independently of the fine dial sec-

tion, and means to set the fine dial section to modify the setting of the coarse dial section with a desired number of fractional coarse steps.

2. The combination of a device which is arranged to be adjusted to any desired setting by coarse steps and by incremental fine steps and including respective rotatable control shafts for the coarse and fine steps, and means operated by said shafts to count and directly indicate the number of turns required for each shaft to cause said device to arrive at said desired setting, the last-mentioned means including a series of rotatable numerical dials one group of said dials indicating a number representing one of said coarse settings, another of said dials indicating a number representing a fractional part of said one of said coarse settings, means to set said group of dials independently of said other dial, and means to set said other dial to modify the setting of said group of dials in accordance with the required incremental fine steps.

3. The combination of a device which is arranged to be adjusted to any desired numerical setting by coarse steps and by incremental fine steps and including respective rotatable control shafts for the coarse and fine steps, a mechanical counting arrangement controlled by said shafts for directly indicating a plural digit number representing said desired setting, said counter comprising at least one rotatable numerical dial which indicates the coarse settings, and another rotatable numerical dial which indicates fractional parts of said coarse settings, means to set said coarse setting dial in steps independently of said other dial, and means to set said other dial so that it is cumulative with respect to the setting of the coarse dial.

4. The combination of a device which is arranged to be adjusted to any desired numerical setting by coarse steps and by incremental fine steps and including respective rotatable control shafts for the coarse and fine steps, a mechanical counting arrangement controlled by said shafts for directly indicating a plural digit number representing said desired setting, said counting arrangement comprising a plurality of numerical dials to indicate successive coarse steps, another numerical dial to indicate the incremental steps, said plurality of numerical dials being coupled directly to each other for cumulative indication, means to set said incremental control dial throughout one revolution independently of said plurality of dials, and means to set said plurality of dials throughout any desired number of revolutions independently of said incremental control dial.

5. The combination according to claim 4 in which means are provided for cumulatively modifying the setting of said plurality of dials when said incremental control dial is rotated through more than one complete revolution.

6. A direct frequency indication arrangement for a frequency selecting system of the type which employs a coarse step-by-step frequency selector and an incremental or fine step-by-step frequency selector, comprising a frequency indicator of the numerical dial counting type, said indicator having first and second dial sections, the first section indicating the coarse steps and the second section indicating the fine steps, means to set said first section under control of the step-by-step setting of said coarse frequency selector and independently of the setting of said fine frequency selector, and means to set said second section under control of the step-by-

step setting of said fine frequency selector to produce a final numerical indication of the frequency of desired setting of said system.

7. A direct frequency indicating arrangement according to claim 6 in which the last-mentioned means includes an adjusting knob which is connected to said second section to operate it in unison therewith, said knob being connected through step-down gearing to one of the dials of the said first section to operate it in step-by-step fixed ratio with respect to said second section.

8. A direct frequency indicating arrangement according to claim 6 in which the last-mentioned means includes an adjusting knob which is connected to said second section to be operated in unison therewith, said knob being connected through an intermittent step-down gearing arrangement to one of the dials of the said first section to operate it in a step-by-step fixed ratio with respect to said second section.

9. A direct frequency indicating arrangement according to claim 6 in which the last-mentioned means includes a common adjusting knob for the fine frequency selector and for said second dial section, said knob being connected to said second dial section to be operated in unison therewith, said knob also being connected serially through an intermittent gear movement and a step-down gearing arrangement and a differential gear to one of the dials of said first section to operate it in step-by-step fixed ratio with respect to said second section.

10. A direct frequency indicating arrangement for a frequency selecting system of the type which employs a coarse step-by-step frequency selector and an incremental or fine step-by-step frequency selector, comprising a frequency indicator of the numerical dial counting type, said indicator having first and second dial sections with the first section having at least two digit dials for indicating the coarse steps, and the said second section having a dial for indicating the fine steps, the dials of the first section arranged to be set in accordance with the step-by-step setting of said coarse frequency selector and independently of the setting of the fine frequency selector, said second section arranged to be set in accordance with the step-by-step setting of said fine frequency selector to produce a final numerical indication of the frequency of the desired setting of said system, a first adjusting knob for controlling said first dial section independently of said second section, a second adjusting knob for controlling the said second dial section, means connecting said second knob through a first differential gearing arrangement to one of the dials of the first section to operate it in fixed ratio with respect to the second dial section, and means connecting said second knob through a second differential gearing arrangement to another dial in said first section to operate it in fixed step-by-step ratio with respect to said one of said dials of the first section.

11. A direct reading frequency indicating arrangement according to claim 10 in which said first knob is also connected to said one of said dials of the first section through said first differential gearing arrangement so that the setting of said one of the dials of the first section can be effected by said first knob independently of said second knob.

12. A numerical counting dial system of the type described, comprising first, second and third indicating dial sections, an adjusting knob for the first and second sections, an adjusting knob for the second and third sections, a gearing ar-

angement between the first knob and the first section for adjusting the first section independently of the second section, means connecting the second knob to the second section for setting it in unison therewith, and other means connecting said second knob to at least one dial of the first section to rotate it in fixed step-by-step ratio with respect to the dial of the second section.

13. A numerical counting dial system according to claim 12 in which the last-mentioned means includes a differential which is also connected to the first knob to enable said one dial of the first section to be set under control of the first knob independently of the second knob.

14. A numerical indicating dial system of the type described, comprising three numerical dials, a first adjusting member for setting the first and second dials independently of the setting of the third dial, a second adjusting member for setting the third dial throughout one revolution independently of the setting of the first and second dials, and means connecting said second adjusting member to said second and third dials to modify their setting in accordance with the total number of revolutions of said third dial.

15. A numerical indicating dial system of the type described, comprising three numerical dials, a first adjusting member for setting the first and second dials independently of the setting of the third dial, a second adjusting member for setting the third dial, a first differential gear which is connected between the first dial and both of said adjusting means, a second differential gear which is connected between the second dial and both of said adjusting means, said differential gears cooperating with both of said adjusting means to enable the first and second dials to be set in fixed ratio by said first adjusting means independently of said second adjusting means, and the setting of said third dial being effected by said second adjusting means independently of said first adjusting means.

16. A numerical indicating dial system of the type described, comprising first, second and third

numerical dials, the second and third dials arranged to indicate coarse steps and the first dial arranged to indicate fractional parts of said coarse steps, a first adjusting knob, a second adjusting knob, a first differential gear controlled by said first knob for controlling the setting of the second dial, said first differential gear also being under control of said second knob to independently control the setting of said second gear

5 without disturbing the first knob, a second differential gear controlled by the first knob for controlling the setting of the third dial, said second differential also being controllable by said second knob to control the setting of said third gear independently of said first knob.

17. A numerical indicating dial arrangement of the type described, comprising first, second and third digit dials, a first adjusting knob, a second adjusting knob, means to set said first

20 dial in unison with the setting of said first knob, an intermittent gear movement controlled by said first knob, a differential gear controlled by said intermittent gear movement, said differential being connected to the second dial whereby

25 said second dial is operated by said first knob in steps of one to ten ratio with respect to the operation of the first dial, an intermittent gear also controlled by said intermittent gear movement, a second differential gear controlled by

30 said intermittent gear, another intermittent gear connected between said second differential and said third dial to cause said third dial to be set in steps by said first knob at the ratio of one to one hundred with respect to the setting of the

35 first dial, and means to control said differentials independently by said second knob to set the second and third dials under control of said second knob independently of the setting of the first dial by said first knob.

ALBERT E. BACHMANN.
